PUMP.

Application filed November 25, 1925. Serial No. 71,328.

This invention relates to pumps particularly for use in deep well pumping and especially oil wells. Great difficulty and inefficiency have heretofore been experienced in oil well pumping, this being caused by the gas contained within the oil as herein-after described.

Wells are ordinarily pumped by the common single acting pump. In this pump the fluid is drawn into the pump chamber between the two valves and discharged from the pump on the same stroke, namely, the up stroke. In this action the fluid follows the running or discharge valve and piston as they travel upwardly, such fluid being drawn through the standing or suction valve which is beneath the discharge valve. On the down stroke the standing valve closes and the column of fluid remains stationary, the piston and discharge valve merely passing through the liquid as they proceed downwardly. In pumping liquids such as oil, wherein is contained a considerable amount of gas, any gas entering the cylindrical chamber between the valves is very difficult to remove, this being due particularly to the compressibility of gas and to the great liquid pressure head on the discharge valve, it being understood that the weight of the column of oil being pumped from the bottom of the well to the surface is on this valve, this pressure at times being 2000 lbs. or over per square inch.

When a pump is in this condition it is generally said to be air bound, and the noise and banging which ensues is erroneously known as "air hammering". The presence of a gas in between two valves in any kind of a liquid pump reduces the volume which is discharged, and if great enough entirely stops the delivery of fluid for the following reason:

A gas, having the qualities of compression and expansion, when drawn through the intake valve by the plunger or piston of the pump on its up stroke, fills the space between the intake and discharge valves. When the piston on its down stroke causes the intake valve to close, the gas instead of lifting the discharge valve is compressed but not sufficiently to overcome the head on the discharge valve. Nothing is therefore discharged from the cylinder by the piston or plunger and the intake valve cannot open on the return stroke because the pressure in the cylinder is greater than the atmospheric

or liquid head beneath the intake valve. The piston or plunger then continues to reciprocate, compressing and expanding the gas between the two valves, without delivering any liquid.

This condition is overcome in air compressors by having the space swept through by the piston reduced to the smallest possible amount. This and other means may be employed where the pump is accessible. In deep well pumps however it is impossible to work to close clearances due particularly to the long pump rods which at each stroke have considerable lost motion due to the stretch of the rods. Therefore, when gas gets into these pumps, the pumps deliver intermittently. Sometimes the pump operates idly for hours without delivering any liquid until leakage of gas therefrom finally permits another intermittent pumping of liquid. The pump may then run well for a short period until the gas pressure has again built up therein, when the idle running process will be repeated. It is obvious that the production of oil could be greatly increased by providing means for ridding the pump of this gas at each stroke of the plunger. It is the primary object of my invention to provide a pump having such means.

In the accompanying drawing I have illustrated one specific embodiment of my invention, but it will be understood that the drawing is not to be construed as defining or limiting the scope of the invention, the claims appended to this specification being relied upon for that purpose.

Referring to the figures of the drawing:

Figure 1 is a longitudinal section view through the plunger of my improved pump.

Figure 2 is a side elevation of the pump within the pump cylinder.

Figure 3 is an enlarged fragmentary section of a detail.

Figure 4 is a cross sectional view taken on line IV-IV of Figs. 1 and 2.

In the drawings, 1 indicates a pump cylinder attached to the lower end of the tubing in a deep well. A ball check valve 2 is provided at the bottom of the cylinder, this being the intake valve of the pump. 3 indicates the lower end of the pump rods attached to the pump plunger 4. The portion 5 of the plunger has oil delivering holes 6 therethrough and is connected to the lower portion 7 by a bushing 8. A valve chamber

9 is provided within the bushing 8 and a ball 10 on a seat 11 provides a check valve which is the discharge valve of the pump.

The member 7 comprises an upper annular end and a lower portion 12 connected by three bars 13, the lower portion providing a fluid pressure chamber receiving a piston 14 therein. The lower end of the chamber is closed by a screw threaded member 15. 10 The piston 14 extends upwardly and the upper portion thereof comprises three vanes 16 directly beneath the ball 10. The lower end of the piston chamber is constructed to form a fluid pressure chamber 17 beneath 15 the bottom of the piston. Fluid pressure is supplied from the chamber 9 to the chamber 17 for raising the piston 14 and ball 10 in the following manner.

The valve seat ring 11 is made reversible, 20 each face thereof being provided with an annular groove 18 therein, the grooves being connected by several holes 19. A duct 20 through one of the bars 13 and a duct 21 provides a by-pass to the chamber 17, 25 several fine screens being provided at 22 to prevent sand and grit from entering the by-pass. It will be understood that the oil or liquid pressure in the chamber 9 is very great and I therefore provide a steel plate 30 23 in the by-pass with a fine hole therethrough to limit the flow of oil to an amount necessary to operate the piston 14.

The chamber 17 has a central outlet port 24. This port is opened and closed by the 35 point of a needle valve stem 25. This stem is slidably mounted within a central cylindrical bore in a connecting member 26, spacing vanes 27 being provided on the stem to space the same from the walls of the bore to 40 permit oil to drain downwardly therethrough as it flows from the outlet port 24.

A member 28 rests on an annular shoulder 29 on the bottom of the member 26, the member 28 comprising annular upper and lower 45 ends connected by three bars 30. Two semi-cylindrical friction plates 31 are normally held outward by a spring 32 into frictional engagement with the walls of the cylinder 1. A compression spring 33 surrounds the valve 50 stem 25 with its ends engaging against the vanes 27 and on a plate 34 resting on shoulders 35. A brass abutment plug 36 is provided above the ball 10 in the chamber 9 to take any upward thrust of the ball to 55 prevent battering thereof.

The check valve 2 is seated on a tapered block 37 within a cage 38 having a rod 39 extending upwardly therefrom. The block can be removed when desired by engaging 60 the rod 39 and can be seated in place through such rod.

The operation of my improved pump is substantially as follows.

With the parts in the position illustrated, 65 the rods 3 and plunger 4 on the up stroke

as indicated by the arrows. The friction plates 31 dragging on the cylinder 1, separate the member 28 from the member 15 as illustrated. This movement releases the compression on the spring 33 whereupon the 70 oil pressure in the chamber 17 forces the valve stem 25 downwardly in a manner permitting oil to flow outwardly through the port 24. It will be understood that this pressure of oil is very great and acts very 75 quickly to compress the spring when the compression of the plate 34 thereon is released. Therefore, upon the upward movement of the plunger, the open port 24 relieves the oil pressure in the chamber 17 and 80 the piston 14 remains in its downward position, leaving the ball 10 seated. A spring 40 is preferably provided for aiding in keeping the piston in its downward position. A charge of oil is therefore drawn through 85 the valve 2 into the cylinder beneath the valve 10.

When the plunger reaches the end of its up stroke and starts downwardly, the friction plates 31 cause the member 28 to contact 90 with the member 15. The plate 34 being supported by the member 28, thereupon compresses the spring 33 and forces the stem valve 25 into the port 24. The design of this spring is such as to allow the other and 95 stronger parts of the mechanism to come into contact after the spring has closed the needle valve. The spring therefore protects the needle valve from injury such as would take place if the same were closed positively. The port 24 being thus closed, a pressure is 100 immediately formed in the chamber 17 and since the bottom area of the piston 14 is greater than the downward fluid pressure area on the ball 10, the piston is immediately 105 moved upwardly and raises the ball, this taking place substantially at the beginning of the downward movement of the plunger.

It is obvious that any gas which has collected in the cylinder beneath the ball 10 110 will be on top of the oil therein and that such gas will immediately be forced upwardly past the valve 10. Thus the valve 10 is positively opened at the beginning of each downward stroke of the plunger in a 115 manner removing any gas between the two valves.

It will be understood that the flow of oil through the by-pass 20 is limited by the fine opening through the steel plate 23 and that 120 the screens 22 prevent any fine sand or grit entering the by-pass 20 and stopping up this fine hole.

The spring 33 prevents injury to the point of the valve stem 25 and the port 24, should the stem accidentally contact against the rod 39. It may be mentioned that the spring 33 would also serve as a shock absorber when seating the valve block 37 by means of the plunger if such seating is de- 125 130

sired, the spring at such time preventing injury of the point of the valve stem 25 by preventing the positive banging of the same into the port 24.

5 It will therefore be seen that my invention positively eliminates the collecting of gas in the pump cylinder and assures that in the pumping operation the greatest efficiency will be secured by pumping a full cylinder 10 of oil at each pump stroke.

Having thus described my invention, what I claim is:

1. In a pump, the combination of a cylinder, a check valve therein, a plunger in the 15 cylinder above the check valve, a check valve carried by the plunger, and means whereby the fluid pressure above the plunger check valve operates to raise such valve on the downward movement of the plunger.

20 2. In a pump, the combination of a cylinder, a check valve therein, a plunger in the cylinder above the check valve, a check valve carried by the plunger, a piston below the plunger check valve, and means including 25 a by-pass from the plunger chamber above the plunger check valve to the piston for moving the piston in a manner to raise the plunger check valve on the downward movement of the plunger.

30 3. In a pump, the combination of a cylinder, a check valve therein, a plunger in the cylinder above the check valve, a check valve carried by the plunger, a piston below the plunger check valve and cooperating with a 35 piston chamber, means providing a by-pass from the plunger chamber above the plunger check valve to the piston chamber, the piston chamber having an outlet port, and means automatically closing such port on the 40 downward movement of the plunger, whereupon fluid pressure within the piston cham-

ber operates the piston to raise the plunger check valve.

4. In a pump, the combination of a cylinder, a check valve therein, a plunger in the 45 cylinder above the check valve, a check valve carried by the plunger, a fluid pressure chamber beneath the plunger check valve, means providing a by-pass from the plunger chamber above the plunger check 50 valve to the fluid pressure chamber, the fluid pressure chamber having an outlet port, and means operated by a frictional engagement against the cylinder for automatically closing such port on the downward 55 movement of the plunger, whereupon fluid pressure within the fluid pressure chamber operates to raise the plunger check valve.

5. In a pump, the combination of a cylinder, a check valve therein, a plunger in the cylinder above the check valve, a check valve carried by the plunger, a piston below the plunger check valve and cooperating with a piston chamber, means providing a by- 60 pass from the plunger chamber above the plunger check valve to the piston chamber, the piston chamber having an outlet port, a needle valve member cooperating with the port, and a member having frictional engagement with the cylinder and having an axial lost motion connection with the plunger, the arrangement being such that when the plunger is moving upwardly the 65 port is open to permit flow of fluid therefrom, and when the plunger starts downwardly the frictional engagement moves the needle to close the port, whereupon pressure immediately builds up in the piston chamber and raises the piston and plunger check 70 valve.
